DESIGN FOR A DRESS ENSEMBLE

Frank Brogan, Larchmont, N. Y.

Application December 5, 1940, Serial No. 97,102

Term of patent 3½ years

To all whom it may concern:

Be it known that I, Frank Brogan, a citizen of the United States and a resident of the city of Larchmont, in the county of Westchester and State of New York, have invented a new, original, and ornamental Design for a Dress Ensemble, of which the following is a specification, reference being had to the accompanying drawing, forming a part thereof.

Fig. 1 is a front view of a dress ensemble showing my design.

Fig. 2 is a rear view thereof.

Fig. 3 is a front view of the dress section of the ensemble shown in Fig. 1.

Fig. 4 is a rear view of Fig. 3.

The characteristic feature of my design resides in the combination on the ensemble disclosed of the specific passementerie pockets and rosettes on the jacket member in association with the particular dress section, as shown.

I claim:

The ornamental design for a dress ensemble, substantially as shown and described.

FRANK BROGAN,
